WITNESS:

J. W. Barron
INVENTOR
BY *Victor J. Evans*

ATTORNEY

UNITED STATES PATENT OFFICE.

JOHN W. BARRON, OF DES MOINES, IOWA.

CONTAINER.

Application filed July 29, 1925. Serial No. 46,894.

This invention relates to improvements in containers and has especial reference to containers for holding powder and similar explosives, an object being to provide means whereby the container may be filled and sealed so as to securely hold the contents therein, and opened for the removal of the contents without the necessity of making a hole or opening in the container and thereby possibly create a spark and ignite the contents of said container.

To this end, the invention provides an opening through which the powder or other explosive may be passed and the opening securely sealed by means of a removable cover plate, novel means being provided for detachably holding the cover plate in place and permanently securing the plate holding means to the container.

With the above and other objects in view, the invention further includes the following novel features and details of construction, to be hereinafter more fully described, illustrated in the accompanying drawings and pointed out in the appended claim.

In the drawings:—

Figure 1 is a sectional view showing a portion of a container with the coverplate removed and the discharge spout extended outward.

Figure 2 is a sectional view showing the container opening sealed.

Figure 3 is an elevation showing the discharge spout in the position indicated in Figure 1.

Figure 4 is a detail perspective view of the cover plate.

Figure 5 is a similar view of the discharge spout.

Referring to the drawings in detail wherein like characters of reference denote corresponding parts, the reference character 10 indicates a keg or container of the type capable of use for holding powder.

Ordinarily, containers for this purpose are not provided with a discharge opening and when the contents are to be removed an opening must be made and in doing this, danger of causing a spark and igniting the powder is present. This disadvantage is overcome in the present invention in which the container is provided with an opening which, after the container has been filled, may be securely closed and thereafter, read-

ily opened without danger of causing a spark.

In carrying out the invention, the container is provided with an opening 11 and this opening is surrounded by side flanges 12, a bottom flange 13 and a top flange 14 which are spaced slightly from the outer surface of the container. These flanges are formed by a plate having an opening which is adapted to register with the opening 11 of the container and the material of the container around the edges of the opening 11 is passed through the opening of the plate and bent over the edges of said plate as indicated at 14a. If desired these bent over edges may be soldered to the plate so as to form a more secure retaining means.

Pivoted within the opening 11 as indicated at 15 is a spout 16 which is normally positioned within the container as shown in Figure 2 of the drawings, the said spout having a lip 17 to engage over the edge of the opening and limit inward movement of the spout. The spout is also provided with spaced flanges 18 which are positioned within the container and which engage the inner wall thereof to limit outward movement of the spout. This spout 16 serves to close the opening 11, but to more securely cover the opening and to hold the spout in closed position there is provided a cover plate 19.

This plate has its side edges relatively inclined and these inclined edges are provided with inturned flanges 20 which are adapted to engage behind the flanges 12, the last mentioned flanges being also relatively inclined. The plate 19 is preferably provided with a felt or other compressible lining 21 which is positioned between the flanges 12, 13 and 14 and said plate and the latter is forced downward over the flanges 12 so that its lower edge engages the flange 13. The flange 14 may then be bent over the upper edge of the plate so that the latter will be securely held in position and the opening tightly closed. The plate may be provided with a lug 22 for use when it is desired to open the container. This is effected by first bending the flange 14 upward and forcing the cover plate in the same direction.

The invention is susceptible of various changes in its form, proportions and minor details of construction and the right is here-

in reserved to make such changes as properly fall within the scope of the appended claim.

Having described the invention what is claimed is:

- 5 In a device as set forth, the combination with a container provided with an opening in its side wall adjacent the top, the edge portion of the opening having wings outwardly bent constituting marginal flanges, of
- 10 a plate having an opening to register with the opening in the container, the marginal flanges laterally overlying the marginal portion of the plate opening, the side marginal flanges downwardly diverging constituting
- 15 guides, a spout pivotally mounted in the first opening to oscillate outwardly and inwardly through the first opening, the inner portion

of the spout having side flanges to engage with side parts of the first opening to limit the spout in its outward oscillatory movement, the upper portion of the spout having a lip to engage the upper part of the first opening to limit the spout in its inward oscillatory movement, a slide closure having side overturned guide flanges diverging downwardly to engage the first guide flanges to close the first opening and prevent outward oscillatory opening movement of the spout, and an upturned flange at the bottom of the plate to limit the closure in its downward closing movement.

In testimony whereof I affix my signature.

JOHN W. BARRON.
